[57] CLAIM

The ornamental design for a male connector, as shown and described.

DESCRIPTION

FIG. 1 is a front view of the new design of a male connector; FIG. 2 is a rear view of the male connector of FIG. 1; FIG. 3 is a top view of the male connector of FIG. 1; FIG. 4 is a bottom view of the male connector of FIG. 1; FIG. 5 is a right side view of the male connector of FIG. 1 (the left side view being a mirror image thereof); and, FIG. 6 is a perspective view from the rear side of the male connector, shown in relation to a female connector component (in phantom line) which is not part of the design claimed herein.
